Fig. 6.

This technical drawing illustrates a mechanical assembly, likely a valve or actuator, in a cross-sectional view. The assembly is mounted on a base plate (40) which features a central slot (15) and a spring (39) positioned below a lever system (33). A vertical rod (34) extends from the base through a housing (36). The rod is connected to a valve element (38) at the top. The housing (36) is secured to a top plate (37) and includes a central bore. A piston (35) is located within this bore, and a spring (38) is positioned between the piston and the valve element. A handle (4) is attached to the side of the base plate, connected to a lever system (33) that provides mechanical advantage for operating the valve. An arrow on the left side of the drawing indicates the direction of force application to the handle.

ADJUSTING DEVICE

Adolf Bargeboer, The Hague, Netherlands

Application June 16, 1931, Serial No. 544,831
In the Netherlands February 2, 1931

10 Claims. (Cl. 236—1)

This invention relates to an adjusting or control device for elements such as valves, electrical contacts and the like, and has generally in view to provide a device of this character which is extremely sensitive in its operation.

According to the invention, a normally straight, elastic leaf element of spring steel or other suitable material has imposed thereon, axially or longitudinally thereof, a practically unvarying load which is substantially equal to the critical collapsing load of the element; i. e., the load under which the internal forces of the element are in equilibrium with the load and have reached their utmost value substantially without bending 5 of the element and which, if exceeded, results in decided bending of the element. By imposing such a load on a normally straight, elastic leaf element it becomes highly stressed and its sensitivity to flexure is vastly increased, so that if it 10 is subjected to a separate bending force it flexes in extremely abnormal proportion to the bending force, depending upon its inherent elasticity.

Further, according to the invention, the bending force to which the elastic leaf element is subjected may have any desired origin. For example, it may originate from a pressure or temperature controlled diaphragm or the like, or it may originate in the element itself, as is the case if the element is, for example, in the form of a bi-metallic strip or of such other inherent nature that it bends in response to variations in temperature. In any event, the element such as a valve, electrical contact or the like to be actuated or controlled is carried by or is connected with the elastic leaf element. It follows, therefore, that since the elastic leaf element flexes in extremely abnormal proportion to the bending force to which it is subjected, the valve, electrical contact or the like is actuated in response to only very slight bending forces and the device therefore operates to perform its work with extreme sensitiveness. Moreover, by limiting the range of flexure of the elastic leaf element, high pressures of the same in its extreme flexed or bent positions will result 20 from only very slight bending forces to which the element is subjected, which is of manifest benefit and importance in many uses of the device.

The elastic leaf element is most sensitive to flexure if the axial load imposed thereon corresponds exactly to the critical collapsing load of said element. However, said element is highly sensitive to flexure if the axial load imposed thereon is in the immediate neighborhood of its critical collapsing load, whether slightly above or below the critical collapsing load.

The invention will be more fully explained with reference to the accompanying drawings, illustrating some embodiments by way of example.

Fig. 1 is a diagrammatic view of a pressure-regulator according to the invention.

Fig. 2 illustrates an electric excess current cut-off device made in accordance with the invention.

Figs. 3, 4 and 5 show an electric temperature-controlling device in two vertical longitudinal sections perpendicular to each other, and in cross section, respectively.

Fig. 6 shows, in vertical section, a gas temperature-controlling device.

Figs. 7 and 8 show two longitudinal sections of another gas controlling device of tubular form.

Figs. 9, 10 and 11 illustrate a steam trap in vertical longitudinal, horizontal longitudinal and vertical cross sections, respectively.

1 is the elastic element consisting of a normally straight flexible strip of steel of suitable length, width and thickness, clamped by means of a spring 5 between the frame 2 and a member 4 pivoted at 3. Attached to the strip 1 is a lever 6 which by means of the member 7 transforms the force exerted on the diaphragm 8 into a moment on the strip 1.

Connected with the leaf element 1 by means of a stem 9 is a valve 10 which is movable between the seats 11 and 12 by flexure of the leaf element. The load imposed on the leaf element 30 by the spring 5 is substantially equal to the critical collapsing load of said element, and is maintained practically unvarying due to the considerable length of said spring 5 and to the lever arm 4 through which the spring operates to load 35 the leaf element. According to the illustration in Fig. 1 it may be assumed that a negative pressure exists below the diaphragm 8 so that through the rod 7 and arm 6 the leaf element is subjected to a movement tending to bend it toward the left. 40 Only a very slight force exerted through the arm 6 is required to flex the leaf element in either direction. Therefore, the instant the negative pressure below the diaphragm 8 becomes a positive pressure the leaf element will be flexed toward the right.

Fig. 2 illustrates an electric overcurrent safety device according to the invention. 15 is an elastic bimetal strip which, at a certain predetermined or critical temperature, is straight and which 50 flexes to the right if its temperature exceeds said critical temperature, and to the left if its temperature falls below said critical temperature. The strip carries a contact 16 for cooperation with an insulated contact 17 which is adjustable

by means of a screw 18. The strip 15 is axially clamped or loaded corresponding approximately to its critical collapsing load at its critical temperature between the frame 2 and lever 4 by means of the spring 5 adapted to be adjusted by means of a screw 19 threaded into the lever 4 and bearing on the frame 2. Now if the temperature of the strip is below its critical temperature its internal movement is such that it bends toward the left and the contact 16 is engaged with the contact 17. If at 20 and 21 the electric current wires are connected through a supply apparatus the current flows through the contacts 17, 16, the strip 15 and the frame 2. In the case of an excessive load the temperature of the strip 15 rises above its predetermined or critical temperature, the internal moment attains the critical value and the strip collapses suddenly into the position shown, producing an instantaneous interruption of the current. By suitably adjusting the screw 19 and the spring 5 it is possible that the strip after cooling does not rebound.

While the flexure of a bimetal strip under normal conditions at the allowable rises of temperature is but very small, this flexure is increased some hundred times by carrying out the invention and moreover, if desired, instantaneously. For this reason the application as a regulator is also possible.

Figs. 3-5 show an electric temperature regulator according to the invention in two vertical longitudinal sections, perpendicular to each other, and in cross section respectively.

35 The elastic bimetal strip 15 is clamped on a block of insulating material 22 and carries at its non-clamped end a contact spring 23 which is just free from an abutment 24. If the temperature is too low contact is made with a contact screw 25 while in the other position the strip is retained by a stop screw 26 provided with an insulated cap. Two lateral springs 27, which are tensioned between the yokes 28 and 29, serve to axially load the strip 15, while the spring 31, the tension of which may be regulated by means of a rotatable knob 30 (Fig. 5) serves for the adjustment of the switching out temperature. The said spring engages a profile piece rigidly secured to the strip 15, whereby a moment is exerted on the strip 15. The current wires are secured to the contact screws 32, 32. By suitable choice of the essential values an instantaneous switching in and out at a temperature interval of 1/100° C. may be obtained.

55 Fig. 6 shows a gas temperature regulator according to the invention.

The bimetal strip 15 is clamped or tensioned by the spring 5 by means of the frame 2 and a lever 4, the tension of the spring being adjustable by means of a screw 33. The strip 15 actuates a valve 35 by means of a valve spindle 34.

The whole is immersed in a liquid chamber of the vessel to be regulated in such a manner that the tube 36 is immersed under the liquid level 65 somewhat more than corresponds with the gas pressure. In this manner a frictionless tightening is obtained. The spring is in this embodiment adjusted so that the first portion of the closing period when the adjusted temperature 70 is attained, elapses very rapidly and the last portion gradually so that the closing is mainly effected very rapidly and further with a small flame the temperature is very accurately controlled dependent on the loss of heat to the exterior. This is obtained by adjusting the tension

of the spring 5 very close by the collapsing load of the strip and by providing the valve 35 with an elastic tightening surface that is more or less uneven. When adjusting for instantaneous opening in both extreme positions a tightening is obtained on the seats 37 and 38. 39 indicates a spring with set-screw 40 to determine the initial moment on the strip 15.

Figs. 7 and 8 show two longitudinal sections of another gas-regulator of tubular form. 10

The operation is similar to that described with reference to Fig. 4, the axial load however being obtained by a spring 41 acting on a yoke 42, 43. The bimetal strip 15 supported at one end is at the other end acted upon by a spring 44 with 15 tension controlling device 45 to determine the moment acting on the strip. Further the strip carries directly the valve 46 co-operating with the seat 47 located opposite an aperture 48 for the passage of the gas. The whole is enclosed in 20 a tubular casing 49 whereby a gas regulator of very compact construction is obtained.

It appears further that the energy which a bimetal strip at a small change of temperature can produce, is much larger when using the invention, than without axial load. On this result the construction of a thermic motor according to the invention is based. It is thereby possible e. g. to use the strip for the reversal of a valve or valves dependent on the periodical heating or cooling of the strip. Now, if the reversal acts to desist the origin thereof (i. e. heating or cooling) then the machine operates automatically. This may be applied e. g. to a liquid-return-device to the evaporators. 35

In Figs. 9-11 this thought is embodied in a condensing vessel.

Fig. 9 is a vertical section, Fig. 10 a horizontal section and Fig. 11 a cross section thereof.

The bimetal strip 15 is tensioned in the frame 40 52 by means of the yoke 50 and the spring 51 attached to the strip. The strip carries a valve spindle with valve 53 adapted to close upon a seat 54 adjustably secured in a body 55 which is laterally tightened by the flanges 56, carrying the frame 52. The valve spindle 53 lifts during the last portion of its opening stroke the spring support 57 against the force of the tensioned spring 58. This spring bears at its other end against a spring support 59, whereby by 50 means of a set-bolt 60 in a casing 61 the spring tension is adjustable.

Now, if steam enters through 62 the strip 15 is heated and it collapses downwardly at a predetermined temperature (e. g. 100° C.) and 55 closes the valve 53 with a blow on its seat 52. Steam thus cannot escape. Now if condensation water accumulates the whole is cooled and at a predetermined temperature, e. g. 90° C., the valve will be pulled open against the 60 pressure. The water escapes, while the valve closes again as soon as the steam reaches the strip 15.

The great advantage of this construction is that the valve is either entirely open or entirely closed and does not occupy a zero-lap position as in most of the condensing vessels. In the latter case the valve will soon leak. The spring 58 serves to take up the transverse load, which at the moment of opening is exerted by 70 the steam pressure. Moreover an adjusting device may be provided for by exerting a variable initial-moment on the strip as e. g. in the regulators according to Fig. 3 (spring 31) Fig. 6 (spring 39) and Fig. 7 (spring 44). 75

Instead of using the spring 58 the valve seat may also be so shaped that on draining a pressure-difference above and underneath the valve body is exerted in such a manner, that a downward pressure on the valve is maintained during the outlet period, which pressure is approximately equal to the pressure on the valve in the closed position.

The above described constructions should be considered as embodiments of the invention, merely given by way of example. The range, however, is much broader.

I claim:—

1. In an adjusting device, an elongated elastic element loaded longitudinally by a substantially unvarying force approximately equal to the critical collapsing load of the element and laterally by a variable internal moment tending to bend said element, the longitudinal force being independent of said internal moment and being applied longitudinally of the element when the same is straight and coincident with the chord thereof when the element is bent.

2. An adjusting device in accordance with claim 1, wherein said elastic element is a bimetallic strip.

3. In an actuating device, an elongated elastic element loaded by a variable load tending to bend said element and also loaded longitudinally by a substantially unvarying force essentially independent of said variable load and of the amount of bending of said element, said longitudinal force being approximately equal to the critical collapsing load of the elastic element and being applied longitudinally of said element when the same is straight and coincident with the chord thereof when the element is bent.

4. In an actuating device, an elongated elastic element loaded laterally by a variable force tending to bend said element and also loaded longitudinally by a force essentially independent of said variable force and of the amount of bending of said element, said longitudinal force being substantially unvarying and approximately equal to the critical collapsing load of the elastic element and being applied longitudinally of said element when the same is straight and coincident with the chord thereof when the element is bent.

5. In an actuating device, an elongated elastic element subjected to the action of a variable moment tending to bend said element and also loaded longitudinally by a substantially unvarying force essentially independent of said variable moment and of the amount of bending of said element, said longitudinal force being approximately equal to the critical collapsing load of the elastic element and being applied longitudinally of said element when the same is straight and coincident with the chord of said element when the same is bent.

6. In an actuating device, an elongated elastic

element subjected to the action of a variable force and of a moment which tend to bend said element and also loaded longitudinally by a substantially unvarying force essentially independent of said variable force, of said moment and of the amount of bending of said element, said longitudinal force being approximately equal to the critical collapsing load of the elastic element and being applied longitudinally of said element when the same is straight and coincident with the chord of said element when the same is bent.

7. In an actuating device, an elongated elastic element subjected to the action of a variable internal moment and of an external moment which tends to bend said element and also loaded longitudinally by a substantially unvarying force essentially independent of said external and internal moments and of the amount of bending of said element, said longitudinal force being approximately equal to the critical collapsing load of the elastic element and being applied longitudinally of said element when the same is straight and coincident with the chord of said element when the same is bent.

8. A device of the character described comprising an elongated elastic leaf element, resilient means acting to impose on said element longitudinally thereof when the same is straight and coincident with the chord thereof when the element is bent, a practically unvarying load which is approximately equal to the critical collapsing load of the element, whereby the sensitivity of said element to flexure is vastly increased, means whereby said element is subjected to a flexing force, and means operable by flexure of said element.

9. A device of the character described comprising an elongated elastic leaf element, means including a spring and a cooperating lever acting to impose on said element longitudinally thereof when the same is straight and coincident with the chord thereof when the element is bent, a practically unvarying load which is approximately equal to the critical collapsing load of the element, whereby the sensitivity of said element to flexure is vastly increased, means whereby said element is subjected to a flexing force, and means operable by flexure of said element.

10. A device of the character described comprising a normally straight, elongated elastic leaf element, resilient means acting to impose on said element longitudinally thereof when the element is straight and coincident with the chord thereof when the element is bent, a practically unvarying load which is approximately equal to the critical collapsing load of the element, means whereby said element is subjected to a bending force, and means operable by bending of said element.

ADOLF BARGEBOER.
